UNITED STATES PATENT OFFICE.

WILLIAM C. JOHNSON, OF WINCHESTER, KANSAS, ASSIGNOR OF THREE-FOURTHS TO LUCIUS O. JOHNSON, MELVEL L. CRITCHFIELD, AND CHARLES F. JOHNSON, OF OSKALOOSA, KANSAS.

BIT.

SPECIFICATION forming part of Letters Patent No. 721,894, dated March 3, 1903.

Application filed November 14, 1901. Serial No. 82,827. (No model.)

To all whom it may concern:

Be it known that I, WILLIAM C. JOHNSON, a citizen of the United States, residing at Winchester, in the county of Jefferson and State 5 of Kansas, have invented a new and useful Bit, of which the following is a specification.

My invention relates to certain improvements in curb-bits adapted for riding or driving, and has for its principal object to construct a bit which may be securely held in position and which will be sufficiently powerful to check a vicious animal with the exercise of comparatively small force.

With this and other objects in view the invention consists in the novel construction and arrangement of parts hereinafter described, illustrated in the accompanying drawings, and particularly pointed out in the appended claim.

20 In the drawings, Figure 1 is a perspective view of a riding-bit constructed in accordance with my invention. Fig. 2 is a transverse sectional elevation of the same. Fig. 3 is a perspective view of a bit of slightly modified construction and more especially adapted for use when driving.

Referring to the drawings, 1 represents oppositely-disposed cheek-plates having central openings 2 for the reception of the headstall 30 of the bridle and provided also with laterally-extended arms 3, the extreme end portions of which are bent inwardly and provided with suitable openings 4 for the reception of a nose-band 5.

35 In the lower ends of the cheek-plates are openings through which extend the opposite ends of a straight or curved mouth-bar 6, and secured to or formed integral with said mouth-bar are side bars or levers 7, the lower ends 40 of which are provided with rings 8 for the reception of the ends of the reins. The upper portion of the side bars 7 is curved, being substantially semicircular in form, and the extreme end of each bar is provided with a 45 slot or opening 9, in which may be secured a

jaw-strap 10, the strap being adjustable and fitted around the lower jaw of the animal.

Projecting inwardly from each of the cheek-plates is a stop-pin 11, which engages with the adjacent side bar or lever 7 and prevents 50 the bit from turning in the horse's mouth and the disengagement of the jaw-strap from its adjusted position under the lower jaw of the animal.

The bit is held in position vertically by the 55 headstalls or cheek-straps of the bridle, and any lateral displacement of the cheek-plate is prevented by the nose-band 5, so that the bit will at all times be properly supported in position and in readiness for use. As the 60 mouth-bar and side arms are rigidly secured together, a pulling strain on the lower ends of the side arms will result in the clamping of the jowar jaw between the mouth-bar and the jaw-strap 10, and sufficient force may be 65 exerted to check a wild or vicious animal, while at the same time a gentle horse may be guided without undue severity.

When the device is employed for driving purposes, the cheek-plates 1', as indicated at 70 Fig. 3, are provided with rings 2', to which may be secured the headstall and check or gag reins, the bit being thus properly supported in position.

While the construction herein described, 75 and illustrated in the accompanying drawings, presents the device in its preferred form, it is obvious that changes may be made in the form, proportions, size, and minor details without departing from the spirit or sacrific- 80 ing any of the advantages of my invention.

Having thus described my invention, what I claim is—

The combination in a curb-bit, of the oppositely-disposed cheek-plates adapted to be 85 firmly secured to the head of the animal, inwardly-projecting stop-pins secured to said cheek-plates, a mouth-bar swiveled in the lower ends of said cheek-plates, depending side arms or levers carried by the mouth-bar 90

and having rein-attaching rings at their lower ends, the upper portions of said side arms being extended upwardly and thence rearwardly and adapted for contact with the stop-
pins to prevent excessive rearward move-
ment of the upper portions of said arms, and
a curb-strap connecting the upper rear por-
tions of said arms.

In testimony that I claim the foregoing as my own I have hereto affixed my signature in ¹⁰ the presence of two witnesses.

WILLIAM C. JOHNSON.
